UNITED STATES PATENT OFFICE.

MARTIN C. BRIGHT, OF INDIANAPOLIS, INDIANA.

REVERSIBLE CONCEALED LOCKING APPARATUS.

Application filed July 10, 1923. Serial No. 650,738.

This invention relates to locking apparatus that is concealed so as to prevent tampering therewith and may have reversible parts to permit the locking apparatus to be readily 5 adapted for right-hand or left-hand doors, and the invention has reference more particularly to coin-controlled locking means for doors, and especially of the type that contains a counter for recording the number 10 of operations of the locking apparatus.

An object of the invention is to provide a concealed locking apparatus which shall be so constructed as to be efficient and reliable, yet having parts of simple design that will 15 not be costly to manufacture, some of which parts may be arranged in reverse position in the locking mechanism.

Another object is to provide an improved lock adapted to be controlled by means of 20 coins for doors of toilet rooms, comfort stations or elsewhere, which may be operated by persons without special instructions, and which shall reliably record the number of 25 operations of the lock.

A further object is to provide an improved coin-controlled lock which shall be so constructed as to obviate the necessity of using delicate springs that might be liable to 30 become broken or deranged, having in view the provision of strong and reliable and well supported parts.

A still further object is to provide an improved coin-controlled lock case in which coins may be securely held, and to provide 35 improved door knobs that shall be so secured in place as to be prevented from being removed excepting by first opening the lock case in a proper manner.

With the above-mentioned and other objects in view, the invention consists in a concealed locking apparatus having novel structure and novel parts and arrangements thereof; and, the invention consists also further in the parts and combinations and 45 arrangements of parts as hereinafter particularly described and further defined in the accompanying claims.

Referring to the drawings, Figure 1 is a 50 fragmentary front view of a door and its casing to which the invention is applied; Fig. 2 is a fragmentary front view of a door and its casing reversely arranged and to which the invention is applied in reverse order relatively to that in the preceding figure; Fig. 3 is a fragmentary edge view of a door and the improved lock thereon; Fig.

4 is a perspective view of the outer one of the door knobs comprised in the invention; Fig. 5 is a rear view of the inner one of the two knobs; Fig. 6 is a vertical sectional elevation of the improved locking apparatus, partially broken away, approximately on the line VI—VI in Fig. 3 but on an enlarged scale; Fig. 7 is a horizontal section of the coin-controlled lock centrally of the lock 65 bolt comprised in the apparatus; Fig. 8 is a perspective view of an improved coin-slot shutter and its controlling device; Fig. 9 is a perspective view of one of the operating and controlling devices of the lock; Fig. 10 70 is a perspective view of another one of the operating and controlling devices of the lock; Fig. 11 is a fragmentary horizontal section showing particularly the mounting of the inner door knob spindle on the lock 75 case and the door; Fig. 12 is a transverse vertical section of the locking apparatus centrally thereof on an enlarged scale and mounted on the door; Fig. 13 is a fragmentary elevation showing a portion of the 80 inside of the front of the lock case and also a device for securing the outside knob securely in place; Fig. 14 is a fragmentary detail showing means for operating a counter; Fig. 15 is the detail of the device shown in 85 the preceding figure, but in a different position; Fig. 16 is a fragmentary sectional elevation showing the mechanism represented in the relative positions of the various parts occupied when the lock bolt has been 90 retracted by means of a coin and the outside knob; Fig. 17 is a view similar to the preceding figure, but showing the different parts in the positions assumed upon the release of the outside knob following the retraction of the lock bolt and preceding the 95 engagement of the lock bolt with its keeper; Fig. 18 is a fragmentary front view showing various parts that are obscured or partially obscured in Figures 6, 16 and 17, the 100 parts being in proper position for retracting the lock bolt by means of a coin; Fig. 19 is a view similar to the preceding figure, but showing the lock bolt as having been retracted and various parts correspondingly 105 arranged; Fig. 20 is a fragmentary horizontal section of the door and its casing and the locking apparatus applied thereto, the door being represented as when being closed and the lock bolt being retracted by contact with 110 its keeper and releasing the coin previously used to retract the bolt to permit the door

to be opened; Fig. 21 is a view generally similar to Fig. 16, but with the lock bolt and various parts shown as having been retracted by means of the inside door knob, 5 resulting in the return of the coin-slot shutter to open position and the operation of the counter or register, the door being then permitted to be opened from the inside; Fig. 22 is a fragmentary front view showing lock 10 parts in proper position to permit retraction of the lock bolt upon an insertion of the coin; Fig. 23 is a view similar to the preceding figure, but with the lock bolt shown as having been retracted by means of a coin; 15 Fig. 24 is a fragmentary view more clearly showing parts partially obscured particularly in Figures 6, 18 and 22; Fig. 25 is a top plan of the improved lock bolt as preferably constructed; Fig. 26 is a perspective 20 view of the locking mechanism slightly modified; Fig. 27 is a horizontal section centrally of the lock bolt in Fig. 26; Fig. 28 is a perspective view of the lock bolt keeper as preferably constructed and adapted to be operated to release the door by a person outside 25 who may be authorized to open the door without the use of a coin, and Fig. 29 is a modified form of lock bolt keeper having means by which the lock bolt may be retracted 30 to open the door from the outside by a person authorized to open the door without the use of a coin.

Similar reference characters in the different figures of the drawings indicate corresponding or like elements or features of construction herein referred to in detail.

In the drawings the numeral 1 indicates a door casing and 2 a door arranged to be locked to the casing; 1' indicates an opposite portion of the door casing and 2' a door reversely arranged to be locked to the casing.

A practical embodiment of the improved locking apparatus as preferably constructed 45 comprises a back or base plate 3 constituting the foundation of the locking apparatus and back of the lock case or casing for enclosing the apparatus, being arranged on the outer side or front of the door and having a bearing boss 4 extending from its back and into a suitable aperture 5 in the door, the back plate 3 being secured to the door by means of screws 6. The back plate 3 has also a bearing boss 7 on its forward side at a lower 50 level than the boss 4, the bosses being midway between the vertical side edges of the back plate to permit the plate to be used on either a right-hand or a left-hand door. The upper portion of the plate 3 has a keeper fixed thereon that comprises a base 8 and a lip 9 extending upwardly therefrom. At a suitable distance below the keeper, the plate 3 has a coin chute base 10 fixed thereon that has a downwardly extending guide 55 projection 11 thereon, the front face 12 of

which is curved and extends upwardly and forwardly from the lower end of the projection to constitute the back of a coin chute which has side plates 13 and 14 extending forward beyond the guide face. Preferably 70 the plate 3 has also a reversing rib 15 extending from the keeper base 8 to the base 10. At the lower end of the plate 3 the plate has two bottom frame members 16 and 17 fixed thereto, preferably by means of foot 75 plates 18 and 19 suitably secured to the back plate.

The covering portion of the lock case comprises a front plate 20, a top plate 21 and side plates 22 and 23, all connected together, 80 preferably integrally. The top and side plates are removably arranged against the edge portions of the back plate 3. The inner side of the lower portion of the front plate is provided with clamp bars 24 and 25 that are normally arranged above the frame members 16 and 17 respectively, being secured to the front plate by means of foot plates 26 and 27 respectively and detachably secured to the frame members 16 and 17 by 85 means of screws 28 and 29 respectively, operating to draw the top plate 21 tightly against the upper edge portion of the plate 3, the lower portion of the lock case otherwise being open to permit removal of coins from the case; but the case is provided with a removable door 30 that has a boss 31 centrally on its inner side in which a cylindrical shank 32 is rotatively arranged, and having a locking bar 33 on its inner end and a collar 34 adjacent to its outer end whereby the shank is retained in place. The outer end of the shank has a suitable key-hole 35 therein to receive a special key whereby to turn the shank to disengage the locking bar from a 90 projection 36 fixed on the back plate 3 and a projection 37 fixed on the inner side of the front plate 20, the locking bar normally engaging said projections to secure the door in place. The front plate has a vertical coin 95 slot 38 therein that is opposite to the coin chute guide 12. The inner side of the top plate 21 has a projection 39 that normally extends into an engagement with the back of the lip 9 to securely hold the upper portion of the lock case in place.

The lock case has two bolt guides therein that are adapted to be arranged reversibly and interchangeably at the inner sides of the side plates 22 and 23; as shown, one of the guides 40 being constructed as a boxing and secured to the back plate 3 against the side plate 22 and having a guide rod 41 fixed to its back and extending beyond its open front towards the side plate 23, and guiding a coil spring 42 seated against the back of the guide structure. The opposite one of the bolt guides 43 is arranged adjacent to the side plate 23 and secured to the back plate 3 and it has a guide 100

bars 44 and 45 projecting from its upper and lower portions respectively. An improved lock bolt 46 is provided which is horizontally arranged in the lock case and mov- 5 ably guided in the bolt guides 40 and 43 and projecting through a suitable opening in the side plate 23, the outer end of the bolt having a beveled face 47. The lock bolt has a bore 48 extending from its inner end, 10 in which the spring 42 is received and seated for automatically projecting the lock bolt. The lock bolt has a recess 49 opposite to the back plate 3 and it has also a wing 50 projecting from its under side, and a wing 50' 15 projecting from its upper side or top to render the bolt reversible. The lock bolt preferably is provided with stop projections 51 on its top and bottom to normally engage the projections 44 and 45 when the lock bolt 20 is projected. When the lock bolt is retracted, its rear end is stopped in the guide 40, and the wings may be adapted to engage the guide to stop the bolt.

The inside door knob is so connected with 25 the door and the lock that its connecting devices are concealed, a collar plate 52 being arranged on the inner side of the door and covering the aperture 5, the outer side of the plate with reference to the lock case, having 30 a bearing collar 53 thereon. The inner side of the collar plate has bosses 54 thereon that extend into the aperture towards the lock case and are engaged by screws 55 inserted therein through suitable holes in the back 35 plate 3 of the lock case. A knob or handle 56 has a shank 57 that is rotatably arranged in the bearing collar 53 and has a retaining collar 58 secured to its inner end to prevent withdrawal of the shank. A spindle 59 is 40 connected to the shank and it has a journal collar 60 thereon that is arranged in the bearing boss 4, the spindle extending a short distance beyond the inner side of the back plate 3. The end portion of the spindle has 45 a lever arm 61 fixed thereto that has a lateral projection 62 thereon arranged to have contact with the wing 50 for retracting the lock bolt, and the spindle has also another lever arm 63 thereon that extends upward 50 and over to the guide 40 to limit the rotary movement of the knob or handle in one direction. The arm 63 has a lateral projection 64 thereon which may be engaged by a dog 65 that is pivoted to an ear 66 on the 55 lower portion of the plate 13 or side of the coin chute, whereby to temporarily prevent rotation of the knob spindle in the opposite direction.

The coin chute base 10 has two pivot bear- 60 ings 67 and 67' in one of which a suitable pivot pin 68 is secured that rotatively supports a hub 69 which has a lever arm 70 fixed thereto that carries a trip pin 71 under the dog 65 to move the dog away from the 65 projection 64. The arm 70 has one edge 72

adapted to rest against the side plate 13 of the coin chute, and the lower portion of said edge has a projection 73 adapted to extend under the side plate and in the edge portion of which is a slot 74. The hub 69 has also 70 a shutter plate 75 fixed thereto that is arranged to swing adjacent to the inner side of the front plate 20 to close the slot 38, the shutter plate having a slot 76 therein through which a coin may be inserted into 75 the coin chute when the shutter plate is suitably positioned, the plate preferably having a gap 77 therein extending from the slot. When the lock mechanism is reversely constructed the pivot pin 68 is placed in the 80 pivot bearing 67.

The lock bolt 46 has a guide projection 78 on its front and has also a transverse slot 79 extending from the rearward side of the projection, and the bolt has also a lateral abut- 85 ment 80 rearward of the slot and at a suitable distance from the projection to constitute a portion of the slot which is designed to receive a coin whereby to retract the bolt.

The upper portion of the bolt has a thin 90 projecting stop plate 81 fixed thereon that may be received into the slot 74, and in order to render the bolt reversible its lower portion has a similar plate 81' thereon. The bolt 46 has also another guide projection 82 95 thereon opposite to the projection 78. A plunger rod 83 is slidingly supported in the guide projections 78 and 82 and has a controlling pin 84 thereon against which a compensating coil spring 85 is seated that is arranged on the plunger rod and seated against the projection 78 through which the rod may be projected past a portion of the abutment 80. The spring 85 is weaker than 100 the spring 42.

An outside knob or handle 86 is provided 110 which has a spindle shank 87 that is removably arranged rotatively in a suitable opening in the front plate 20 of the case and so as to be opposite to the boss 7, and it has a circumferential groove 88 that is normally adjacent to the inner side of the plate 20. The shank receives a squared portion 89 of a spindle 90 that is rotatively supported in 115 the boss 7. The spindle has a lever arm 91 fixed thereon that bears against the end of the boss 7 and extends upward adjacent to the plunger rod 83 and has a slot 92 therein receiving the control pin 84. The arm has a lateral finger 93 thereon to temporarily support an edge portion of a coin when received in the slot 79. Preferably the arm 91 has a slot 94 therein receiving a stop projection

95 fixed on the end of the boss 7 to limit the rotary movement of the handle or knob and also the swinging movement of the lever arm. The knob 86 is hollow and has a coil spring 96 seated therein that is under compression against the spindle portion 89 for maintaining the arm 91 accurately in posi- 125 130

tion to be guided against the boss 7. The inner side of the front plate 20 has two vertical guides 97 and 98 fixed thereon on opposite sides respectively of the knob 5 spindle, and the front plate preferably has also a guide stud 99 thereon below the spindle. A locking plate 100 is vertically arranged in the guides 97 and 98 and it has an opening 101 therein into which the shank 10 87 may be inserted, and a slot 102 of less width than the diameter of the shank, the portions of the plate at the sides of the slot being received in the groove 88 and prevent withdrawal of the shank from the lock case. 15 The locking plate has a slot 103 receiving the guide stud 99 and it also has a finger 104 on its lower end which is adjacent to the locking bar 33. The locking plate 100 descends by the force of gravity and may 20 be elevated to release the shank 87 when the door 30 is removed from place.

A suitable counter or register is arranged in the upper portion of the lock case and may comprise a suitable open front casing 25 105 that is secured to the back plate 3 and supports a shaft 106 on which numbered disks or wheels 107 are arranged so as to be visible through a sight-opening 108 provided in the front plate 20. The counter may be 30 of well-known construction and its shaft extends through one side of its casing and has an operating head 109 adjustably secured thereto which has a fork 110 on one side thereof into which extends a suitable lever arm 111 35 which is fixed to the lever arm 70. The head 109 has a pointed or wedge-like projection 112 on its upper side to which a guide-bar 113 is pivoted and guided in an ear 114 supported adjacent to one side of the lip 9, a 40 similar ear 114' being arranged on the opposite side of the lip to be utilized when the mechanism is reversely arranged. The guide-bar 113 has a collar 115 loose thereon that has a blunt wedge face in contact with the projection 112 and forced thereto by a 45 spring 116 under compression between the collar and the ear 114, the spring with the collar and the projection being designed to complete the tilting movement of the head 50 109 after it has been moved slightly more than one-half of its range of movement, for the purpose of insuring complete movement of the arm 70 and accuracy of operation of the shutter plate and the lock bolt and also 55 the counter wheels or disks.

Various parts of the lock mechanism may be variously modified and differently arranged, the lock case being constructed substantially as herein-before described, with 60 changes of location of apertures or slots that may be necessitated to accommodate the arrangement of parts in modified construction. The lock case has a back plate 3' on which is a bearing boss 7' to guide the outside knob spindle. The back plate has a coin chute 65

thereon comprising a base portion 10' and side plates 13' and 14'. The outside knob spindle 60' is connected with the back plate of the lock case and has a lever arm 61' connected thereto that has a projection 62', and it has also a lever arm 63' thereon that has a projection 64' thereon. A dog 65' is pivotally supported substantially as above indicated so as to swing into engagement with the projection 64'. A pivot 68' is suitably supported adjacent to the coin chute and supports a hub 69' to which a lever arm 70' is fixed, the arm carrying a pin 71' whereby to lift the dog 65'. The arm 70' has a side portion 72' adapted to be stopped against the adjacent side of the coin chute, and the arm has also a projection 73' extending under the coin chute. A shutter plate 75' is fixed to the hub 69' to close or open the coin chute. The back plate 3' has also a lock bolt guide 43' thereon which has a base 45'. The lever arm 70' has an arm 111' that is connected with the fork 110 to operate the counter. The outside knob has the squared 50 spindle part 89' to which a lever arm 91' is connected.

A modified lock bolt 46' is movably guided in the guide 43' and it has upper and lower plates 117 and 118, the bolt having a recess between the plates. The plates are of such length as to permit a coin to pass from the coin chute into the recess at the ends of the plates. The upper portion of the lock bolt has an abutment 119 and the lower portion has a relatively longer abutment 120, the abutments being separated from the ends of the upper and lower plates to constitute a coin slot 79' to receive a coin from the coin chute when the lock bolt is projected. The lock bolt has a rear end member 121 and a projection 122 on the lower portion of the bolt that is designed to be stopped when the lock bolt is retracted, against a guide bar 123 fixed on the back plate 3'; and the projection 122 has a downwardly extending wing 124 arranged to be engaged by the projection 62' to retract the lock bolt. The lock bolt has a guide rod 125 that is secured to the member 121 and extends through the guide 123, and a coil spring 126 is arranged on the rod and seated against the end member 121 and the guide 123, for projecting the lock bolt. A plunger head 127 is arranged between the plates 117 and 118 and is movable towards the end member 121, being guided upon a rod 128 that is secured to the bolt 46' and extends to the head and also through the end member 121, a compensating spring 129 that is weaker than the spring 126 being arranged on the rod between the head and the member 121. The head 127 has an arm 130 fixed thereto that has a guide bar 131 thereon that is guided by the guide 43'. The arm 130 has also a plunger rod 132 to be moved to a coin when received 130

in the coin slot, the coin being temporarily supported in the coin slot on a finger 131 fixed to the arm 130. The lock bolt has a stop pin 51' thereon that engages the member 45' when the lock bolt is projected. The arm 130 is arranged so as to be engaged by the lever arm 91' for retracting the lock bolt with the aid of a coin.

For the purpose of enabling a janitor or other person authorized to gain admission without expending a coin to open the door of the room, an improved lock bolt keeper is provided which may be variously constructed to the end that the lock bolt may, without drawing it from the keeper, be released from the door casing or frame. As preferably constructed the improved keeper comprises a base plate 134, which is firmly secured to the door casing, and a box 135 is connected by means of a suitable hinge 136 to the base plate, the box normally covering the projected portion of the lock bolt and having a lock member 137 which may be provided with any suitable locking means to lock the box to the base plate, being provided with a key barrel 138.

A modified form of keeper comprises a box 139 that is secured by means of screws 140 to the door casing, the box having an opening to receive the projected portion of the lock bolt. The box-like keeper is provided with suitable lock mechanism as may be desired that has a rotary key barrel 141 which operates and controls two fingers 142 and 142' arranged adjacent to the end of the lock bolt so that when either one of the fingers is moved against the end of the lock bolt the bolt is forced out of the keeper and permits the door to be opened.

In practical use, the door being closed and locked, with the locking mechanism set as in Figs. 6, 7, 12, 18, 22 and 24, a coin 143 is inserted through the slot 38 and into the coin chute through the slot 76 in the shutter, the coin passing into the slot 79 in the lock bolt in which it is supported by a portion of its edge on the finger 93. If the knob or handle 86 be turned so as to slightly compress the spring 85, the arm 91 moves the plunger rod 83 against the coin and the coin is forced against the abutment 80 and causes retraction of the lock bolt and compression of the spring 42 while the finger 93 continues to support the coin, after which the door is swung open with the mechanism set as in Fig. 16. When the lock bolt has been retracted the coin slot 38 will have been closed by the shutter and the arm 111 will have tilted the head 109 so as to be in proper position for operating the counter. The outside knob or handle may now be released which permits action of the spring 42 and the lock bolt to be thereby projected, the arm 91 being carried back by means of the spring 85 and turning the knob to its original position, the

mechanism being set as in Fig. 17. A person entering the room draws the door shut, or it is forced shut by its spring-hinges, the beveled end 47 striking the keeper as in Fig. 20 and being forced back permits the door to be closed, the retracting lock bolt carrying the coin in the slot 79 back until the coin is pushed off from the end of the finger 93 and drops down into the lower portion of the lock case, with the mechanism positioned as in Figs. 20 or 21, the lock bolt being quickly projected automatically into the keeper when the door is closed. When the lock bolt is being retracted by means of a coin the coin engages the lever arm 70 and swings it back and thereby causes the shutter to swing across the coin slot, the dog 65 being forced up from the projection 64. In case a second coin is inserted through the coin slot 38 before retracting the lock bolt, the second coin will first rest upon the first coin, as in Fig. 8, but will drop on to the plate 81 when the first coin is forced from under it upon backward movement of the lock bolt, as seen in Fig. 19 without interfering with the operation of the mechanism. The door may now be opened from the inside upon the turning of the knob or handle 56 which causes the arm 61 to retract the lock bolt and the projection 64 to swing the arm 70 back to its original position, as seen in Fig. 21, causing the arm 111 aided by the spring 116 and the wedging devices to tilt the head 109 so as to operate the counter, the shutter 75 at the same time being swung back so as to uncover the coin slot and the coin chute, the movements of the different elements being positive upon the necessary operation of the door knob. After the door has been opened from the inside and a person permitted to pass out, the door is automatically closed as usual, the locking mechanism being again set ready to be operated by a coin as above described.

In the operation of the modified mechanism, a coin entering the coin chute falls into the coin slot 79' and is stopped and retained by the finger 133, and the spindle 89' of the outside handle being turned, the arm 91' moves the plunger rod 132 against the coin which being forced against the abutments 119 and 120 causes the lock bolt to be retracted. The coin carried back with the lock bolt engages and pushes back the lever arm 70' which in turn causes the dog 65' to be moved away from the projection 64', the shutter 75' being at the same time moved to a closed position; the coin is dropped in the manner above described and the lock bolt is retracted and other operations performed when the inside knob is turned to cause the projection 62' to engage the wing 129 whereby to retract the lock bolt.

It will be understood from the foregoing description that the janitor or attendant may

have a special key whereby he may operate the private lock bolt releasing keeper and permit the door to be opened without operating the lock and the counter or register.

Having thus described the invention, what is claimed as new is,—

1. A locking apparatus including a spring-projected lock bolt having an abutment, a movable device to engage a coin on the abutment to retract the lock bolt, a lever arm to actuate the device, a finger controlled by the arm to support a coin on the abutment, a shutter having an arm to be partially operated by the coin, means to automatically complete the operation of the shutter arm, and means to actuate the lever arm.

2. A locking apparatus including a spring-projected lock bolt having a coin-receiving slot therein, a movable device to engage a coin in the slot to retract the lock bolt, a lever arm to actuate the movable device, a finger movable by the arm to support a coin in the slot, and means to actuate the arm.

3. A locking apparatus including a spring-projected lock bolt and a plunger movably mounted thereon, the lock bolt having a coin-receiving slot and an abutment at one side of the slot in range of the plunger, means to move the plunger towards the abutment for engaging a coin in the slot to retract the lock bolt, and a spring to retract the plunger.

4. A concealed locking apparatus including, a case, a lock bolt movably guided in the case and having a guide thereon and also an abutment opposite to the guide, a spring seated in the case and on the bolt to project the bolt, a plunger rod to retract the lock bolt by means of a coin on the abutment and movably arranged in the guide and projectible towards the abutment, means to move the plunger rod and a spring seated on the guide and having connection with the plunger rod to retract the rod.

5. A concealed locking apparatus including a case, a lock bolt movably guided in the case and having a coin-receiving slot, a projecting-spring for the lock bolt, a plunger rod guided to be moved on the lock bolt to engage a coin in the slot and thereby retract the lock bolt, a handle shank rotatively supported by the lock case and having a lever arm to operate the plunger rod, and a retracting-spring for the plunger rod.

6. A concealed locking apparatus including a lock case having a coin chute, a lock bolt movably guided in the lock case and having a coin slot, a spring co-operating with the case to project the lock bolt, a plunger rod guided on the lock bolt to be projected to the coin slot, a spring co-operating with the lock bolt to retract the plunger rod, a handle shank rotatively supported by the lock case, a lever arm secured to the shank to operate and project the plunger rod, and a movable finger controlled by the

lever arm to temporarily support a coin in the coin slot.

7. A reversible locking apparatus including a lock case with a slot in its front portion, the back portion having a base fixed thereon provided with a coin chute, the base having two pivot bearings spaced apart on one and the same horizontal plane, a lock bolt horizontally movable in the lock case below the coin chute and having a coin-receiving slot therein, a pivot supported by one of the two pivot bearings, a shutter plate and a lever having a hub common to both and supported on the pivot, the lever being in the path of a coin in the slot to be operated by the coin, and means movable to engage the coin to retract the bolt.

8. A locking apparatus including a spring-projected lock bolt having an abutment, a movable device to engage a coin on the abutment to retract the lock bolt, a lever arm to actuate the device, a finger controlled by the arm to support a coin on the abutment, a movable shutter having a shutter arm to be actuated by the coin, means to actuate the lever arm, a counter to be actuated by the shutter arm, and means adapted to aid the shutter arm to actuate the counter and automatically to complete the operation of the counter following partial operation thereof by the shutter arm.

9. In a locking apparatus, the combination of a spring-projected lock bolt to be coin-retracted, a movable finger to temporarily support a coin in connection with the lock bolt, a movable device to engage the coin and thereby retract the lock bolt, a lever arm to actuate the device and to control the finger, means to actuate the lever arm, a movable coin-slot shutter having an actuating device, a counter and rotary operating shaft therefor, and means connected with the operating-shaft to be actuated by the actuating device to turn the operating-shaft provided with means automatically to further turn the shaft and to further move the shutter.

10. In a concealed locking apparatus, a controlling device comprising a hub provided with a pivot to support it, a shutter plate and an operating-arm fixed to the hub, the operating-arm having an edge adapted for engagement with a stop device and having also a slot extending from a point beyond said edge distant from the hub, and means to actuate the operating-arm.

11. In a concealed locking apparatus, a lock bolt and a connecting device thereon, a bolt-retracting device comprising a rotatively-supported spindle having a lever arm fixed thereto provided with a finger on one edge thereof to support a coin in a lock bolt, the bolt having a slot to receive a coin the lever arm having also a longitudinal slot therein beyond the finger to receive the con-

- necting device on the lock bolt, said device being engageable with a coin in the slot and a handle having connection with the spindle.
12. In a concealed locking apparatus, a controlling device comprising a hub provided with a pivot to support it, means to actuate the hub, a shutter plate and an operating-arm fixed to the hub, the shutter plate having a coin-receiving slot therein, the operating-arm having an edge adapted for engagement with a stop device and having also a projecting portion beyond said edge and a slot in said projecting portion.
13. In a concealed locking apparatus, the combination of a horizontally movable lock bolt having a coin-receiving slot, a plunger rod movably mounted on the lock bolt to be projected to said slot, and a pivoted lever arm having operative connection with the plunger rod and provided with a finger extending below said slot to temporarily support a coin in the slot and permitting movement of the lock bolt to push such coin off the finger.
14. In a concealed locking apparatus, the combination of a longitudinally-movable lock bolt having an abutment and a coin slot adjacent to the abutment, and a plunger rod movably guided on the lock bolt to be projected towards the abutment, with a device movably supported to support an edge portion of a coin in said slot, and means to hold the device to permit movement of the lock bolt to carry the coin from the device.
15. In a concealed locking apparatus, the combination with a register having an operating-shaft, of a head secured to the operating-shaft and having a wedge-like projection thereon, a guide rod pivoted to said projection, a guide for the rod, a collar loose on the rod and having a wedge face engaging said projection, a spring on the rod under compression against the guide and the collar, and a pivoted operating-arm having a lever arm connected with the head to move the head alternately in opposite directions.
16. In a concealed locking apparatus, a locking means comprising a bolt with a projecting-spring at one end thereof, the opposite end of the bolt being beveled, the bolt having two guides and also an abutment on one side thereof and a slot in a portion between the abutment and one of the guides, a plunger rod movably mounted in the guides to engage a coin in said slot against said abutment and having a projection thereon between said guides, means connected with said projection to actuate the rod, and a coil spring on the rod seated on said one of the guides and also on the projection and retracting the rod from the abutment.
17. In a concealed locking apparatus, the combination with a lock case, of a vertical coin chute fixed in the case, a lock bolt horizontally movable below the coin chute and having a thin stop plate on one side of its upper portion, the bolt having a coin-receiving slot at one end of said plate, an operating-arm pivotally supported adjacent to one side of the coin chute and stopped against the chute, the operating-arm having a projection extending under the side of the chute and having also a slot extending through the projection to receive said plate, and a shutter connected with and operated by the operating-arm.
18. In a concealed locking apparatus, the combination with a lock case, of a coin chute supported in the case, a lock bolt movably guided in the case and having a coin-receiving slot, a spring to project the lock bolt, a shutter pivotally supported adjacent to the coin chute and having an operating-arm connected therewith to be engaged and moved by a coin in said slot, the operating-arm having a lifter pin thereon, a spindle rotatively connected with the lock case and having a lever arm fixed thereto and operating to return the operating-arm, means actuated by the lever arm to engage the coin to retract the lock bolt, and a dog pivotally supported to engage and lock the lever arm and to be disengaged by said lifter pin.
19. In a locking apparatus, the combination with a lock casing, and a register supported in the casing and having a rotary shaft, of a head adjustably secured to said shaft and having a wedge-like turning-device thereon, a lever arm movably supported in the casing and having connection with the head to rotate the shaft, automatically-acting means supported by the casing and engaging the turning-device to further rotate the shaft, and a shutter controlled by the lever arm.
20. In a coin-controlled locking apparatus the combination, with a lock casing and a counting device supported in the casing and having a rotary operating-shaft, of a spring-projected lock-bolt in the casing to be coin-retracted, means to temporarily support a coin in connection with the lock bolt, a movable device to engage the coin and thereby retract the lock bolt, a movable coin-slot shutter supported in the casing to be moved by means of the coin, means enabling the moving shutter to turn the operating-shaft, and means automatically to further turn the operating-shaft and to further move the shutter including opposite co-operating cam devices and a spring supported by the casing and constantly tensioning one of the cam devices.

In testimony whereof, I affix my signature.

MARTIN C. BRIGHT.
